UNITED STATES PATENT OFFICE.

ESKEL L. JOHNSON, OF CLARISSA, MINNESOTA.

ALIGNMENT DEVICE FOR COW STANCHIONS.

Application filed May 4, 1923. Serial No. 636,623.

To all whom it may concern:

Be it known that I, ESKEL L. JOHNSON, a citizen of the United States, residing at Clarissa, in the county of Todd and State of Minnesota, have invented certain new and useful Improvements in an Alignment Device for Cow Stanchions, of which the following is a specification.

This invention relates to improvements in cow stanchions and more particularly to a supporting device therefor.

The primary object of the invention is to provide a novel device for supporting cow stanchions, whereby all of the stanchions can be independently adjustable in relation to the curb, so that all of the animals can be properly positioned in relation to the curb irrespective of the size thereof.

Another prime object of this invention is the provision of a clamping member for engaging the stanchion beam or supporting bar irrespective of the size and configuration thereof and means carried by the clamping bar for holding a stanchion in such a manner that the same can be adjusted in a horizontal plane toward and away from the curb of the stall so as to permit all of the cows to keep in line with the gutter or curb.

A still further object of the invention is to provide a novel alignment device for cow stanchions of the above character, which will be durable and efficient in use, one that will be simple and easy to manufacture, and one which can be placed upon the market at a reasonable cost.

With these and other objects in view, the invention consists in the novel construction, arrangement and formation of parts, as will be hereinafter more specifically described, claimed and illustrated in the accompanying drawings, in which drawings:

Figure 1 is an end elevation of the improved alignment device showing the same connected to a stanchion beam or bar and supporting a cow stanchion.

Figure 2 is a side elevation of the improved alignment device showing parts thereof in section and connected to stanchion beam and supporting a cow stanchion, the beam being shown in transverse section.

Figure 3 is a detail transverse section through the improved alignment device taken on the line 3-3 of Figure 2.

Figure 4 is a detail perspective view of the improved supporting bar for the cow stanchion.

Figure 5 is a detail perspective view of one of the clamp members for engaging the stanchion or supporting beam.

Referring to the drawings in detail, wherein similar reference characters designate corresponding parts throughout the several views, the letter A generally indicates the improved stanchion alignment device, B a stanchion supported thereby and C a stanchion beam or support.

The stanchion B and the beam C are of the usual or any preferred construction and therefore a detailed description thereof is deemed superfluous. The beam C has been shown of rectangular configuration, but it is to be understood at this point that the alignment device can be associated with tubular stanchion beams or supports. The extreme upper end of the cow stanchion beam carries a link 5 and a connecting ring 6 and this ring 6 can be connected in any other preferred way to the stanchion beam, such as by a swivel or the like.

The improved alignment device A consists essentially of the novel clamping and supporting device D and the supporting cow stanchion holding member E.

The clamping means D is provided for engaging different sizes of stanchion beams and includes a pair of companion members 10 and 11 which are movable toward and away from each other. Each of the companion members 10 and 11 embody an arm 12 of substantial U-shaped in cross section for slidably receiving the supporting member E of the cow stanchion B and a clamping jaw face 13. The clamping jaw faces 13 can be made of any desired configuration to conform to the shape of the cow stanchion supporting beam C, which the alignment device A is to be associated with. As shown the jaw faces are of a flat construction and are bored as at 14 to receive bolts 15 which extend through the bar C. The arms 12 are slotted as at 16 and these slots extend longitudinally of the arms.

The supporting device E of the cow stanchion B comprises a lower supporting bar 20 of a substantial arcuate configuration having its opposite terminals provided with curved extensions 21 which in turn support inwardly extending arms 22. These arms 22 terminate short of one another and are arranged directly above the bar 20. These arms 22 are provided with spaced bolt openings 23 which are adapted to receive the

clamping bolts 24. These bolts 24 extend through the guide slots 16 formed in the arms 12 of the clamping members 10 and 11 and serve to hold the clamping members in 5 adjusted position on the arms 22 against movement. By this construction it can be seen that the bolts 24 can be loosened and the clamping members 10 and 11 slid upon the arms 22 so that the distance between the jaw 10 faces 13 can be varied to receive any size of stanchions supporting bar C.

The upper edge of the bar 20 is provided with a plurality of spaced grooves 23 and these grooves 23 gradually narrow toward 15 their outer ends to provide restricted neck portions so as to prevent the accidental displacement of the supporting ring split therefrom of the cow stanchion B.

In use of the improved cow stanchion 20 alignment device, the members 10 and 11 are adjusted so as to engage the beam C and the ring 6 is placed in one of the notches 23 according to the size of the cow, so that the 25 cow will be moved toward or away from the gutter and thus permit all of the cows to be adjusted in relation to the gutter and brought into proper alignment therewith. Owing to the fact that the stanchion is permitted to swing back and forth, there is no 30 need of adjusting the lower end thereof. The bar 20 is made slightly arcuate so as to insure proper slack of the stanchion when the ring 6 is placed in either one of the five 35 notches 23. While I have shown only five notches, it is to be understood that more or less can be provided if so desired.

Changes in details may be made without departing from the spirit or the scope of 40 this invention.

What I claim as new is:—

1. The combination with a cow stanchion and a supporting stanchion beam, of an alignment device for the stanchion comprising a supporting bar arranged to extend at 45

right angles to the cow stanchion, arms carried by the bar and disposed above the same having the terminals thereof arranged in spaced relation, adjustable clamping members carried by the arms for engaging the beam, a ring carried by the bar for engaging a stanchion to permit the stanchion to be adjusted in a horizontal plane toward and away from said stanchion beam. 50

2. The combination with a cow stanchion and a stanchion supporting beam, of a stanchion alignment device embodying a curved supporting bar, inwardly extending arms carried by the terminals of the bar and arranged above the same, adjustable clamping members carried by the arms for engaging the beam, means for connecting the clamping members to the beam, the bar having spaced notches formed in its upper surface, and a ring to be connected with a cow 55 stanchion adapted to fit in any one of said notches.

3. In an alignment device for cow stanchions comprising a supporting bar having a plurality of spaced adjustment notches in its upper edge, inwardly extending arms carried by the terminals of the bar terminating in spaced relation to one another and arranged above the bar, a pair of clamping members each including a guide arm substantially U-shaped in cross section slidably mounted upon the arms of the bar, jaw faces formed on the inner ends of the guide arms for engaging a cow stanchion supporting beam, the guide arms having longitudinally extending slots therethrough, and bolts extending through said slots and said arms. 70

In testimony whereof I affix my signature 75 in presence of two witnesses.

ESKEL L. JOHNSON.
